ATTORNEY.

UNITED STATES PATENT OFFICE.

JOHN P. STEPP, OF BROOKLYN, N. Y., ASSIGNOR TO JOHN H. WALBRIDGE, OF SAME PLACE, AND EDWARD P. HOFF, OF NEW YORK, N. Y.

INKSTAND.

SPECIFICATION forming part of Letters Patent No. 349,411, dated September 21, 1886.

Application filed July 27, 1886. Serial No. 209,211. (No model.)

To all whom it may concern:

Be it known that I, JOHN P. STEPP, a resident of Brooklyn, in the county of Kings and State of New York, have invented an Improvement in Inkstands and Analogous Devices, of which the following is a full, clear, and exact description, reference being made to the accompanying drawings, in which—

Figure 1 represents a side elevation, partly in section, of my improved inkstand, showing it closed. Fig. 2 is a similar view of the same, showing it open. Fig. 3 is a top view of the same. Fig. 4 is a vertical section on the line *c c*, Fig. 1. Fig. 5 is a longitudinal section of a modification of the same.

The object of this invention is to combine an inkstand or other vessel with a lid or cover and with a frame, all arranged so that on sliding the inkstand or vessel into a certain position the cover will be swung open, while on sliding it into another position the cover will be swung closed, all as hereinafter described.

In the drawings the letter *A* represents the vessel, which may be used for holding ink or any other suitable substance. This vessel is, in Figs. 1, 2, 3, and 4, shown to rest on a supporting-frame, *B*, to which, at *a*, the cover *C* is pivoted. The supporting-frame *B* rests on and is adapted to slide upon a main fixed frame, *D*. This fixed frame *D* has uprights *b*, in which are upright slots *d*, and into these slots enter pins *e*, that project horizontally from the cover *C* of the vessel *A*. When the vessel *A* is in the position shown in Fig. 1—that is, with the cover resting on it—the pins *e* of the cover will be in the lower part of the slots *d*; but when the vessel, together with its frame *B*, is slid forward into the position shown in Fig. 2 the pins *e* will slide up in the

slots *d* and the cover *C* will be opened. The frame *B* is by preference provided with a projecting handle, *f*, by which it can be pulled forward and pushed backward. When pushed backward from the position shown in Fig. 2 to that shown in Fig. 1, the cover will be shut down over the vessel.

The entire device makes a convenient inkstand, which the user, by pulling on the handle *f*, can draw toward himself and at the same time open, and it will be shut whenever he pushes it from him, the frame *D* being regarded as stationary for this purpose.

In order to prevent any lateral displacement of the sliding vessel *A*, it may be guided between rails on the frame *D*; or a pin, *g*, may project downwardly from the frame *B* through a slot, *h*, in the frame *D*, as in Figs. 1 and 2, to guide the sliding parts, and also to serve as a stop to limit their movement.

Although the sliding frame *B* is convenient, it is not necessary, and in Fig. 5 I have shown the vessel *A* placed directly upon the stationary frame *D* and having the cover *C* pivoted to it at *a*, the said cover having the pins *e*, that extend through the slots *d* of the frame *D*. In this case the handle *f* may be attached directly to the vessel *A*.

I claim—

The combination of the sliding vessel *A* with a pivoted cover, *C*, stationary supporting-frame *D*, having slotted uprights *d*, and with the horizontal pins *e*, that project from the cover *C* through the slots of said uprights, substantially as herein shown and described.

JNO. P. STEPP.

HARRY M. TURK.

Correction in Letters Patent No. 349,411.

It is hereby certified that the name of one of the assignees in Letters Patent No. 349,411, granted September 21, 1886, upon the application of John P. Stepp, of Brooklyn, New York, for an improvement in "Inkstands," should have been written and printed *Edward P. Haff* instead of "Edward P. Hoff"; and that the said Letters Patent should be read with this correction therein that the same may conform to the record of the case in the Patent Office.

Signed, countersigned, and sealed this 5th day of October, A. D. 1886.

[SEAL.]

H. L. MULDROW,
Acting Secretary of the Interior.

Countersigned:

R. B. VANCE,

Acting Commissioner of Patents.
